INVENTOR.
Joseph F. Lynch
BY *George W. Lister*
ATTORNEY

UNITED STATES PATENT OFFICE.

JOSEPH F. LYNCH, OF STOCKTON, CALIFORNIA.

DIRECTION SIGNAL FOR AUTOMOBILES.

Application filed August 28, 1922. Serial No. 584,641.

To all whom it may concern:

Be it known that I, JOSEPH F. LYNCH, a citizen of the United States, residing at Stockton, county of San Joaquin, State of California, have invented certain new and useful Improvements in Direction Signals for Automobiles; and I do declare the following to be a full, clear, and exact description of the same, reference being had to the accompanying drawings, and to the characters of reference, marked thereon, which form a part of this application.

This invention relates to improvements in direction-giving signal device for automobiles, of a kind which may be readily seen either by night or day, and from both ends and sides of the vehicle.

The present invention is particularly an improvement over the signal shown in my Patent No. 1,357,504, dated November 2nd, 1920, my main object now being to simplify the construction and installation of the device from what is shown in said patent, without detracting from the efficiency of operation or visibility of the signal.

A further object of the invention is to produce a simple and inexpensive device and yet one which will be exceedingly effective for the purposes for which it is so desired.

These objects I accomplish by means of such structure and relative arrangement of parts as will fully appear by a perusal of the following specification and claims.

In the drawings similar characters of reference indicate corresponding parts in the several views:

Fig. 1 is a perspective outline of an automobile showing my improved signal installed thereon.

Fig. 2 is an enlarged side view of one of the signal members.

Fig. 3 is a rear end view of the same.

Fig. 4 is a plan view of the signal-motion control means.

Fig. 5 is a detached end view of a contact member.

Referring now more particularly to the characters of reference on the drawings, the numeral 1 denotes a pair of bracket or frame structures, adapted to be fixed onto both rear or front wheel fenders 2 of an automobile, preferably at the highest point thereon.

Pivoted in the brackets on shafts 3 extending longitudinally of the vehicle are the

signal members 4, extending in a plane at right angles to the shafts, and preferably shaped to simulate arrows, both of which point in the same general direction at all times.

These signals are hollow casings, a portion of both front and rear sides of which are cut away substantially arrow shaped and covered with red or other colored glass or other translucent material.

In each casing is removably mounted an electric light bulb 6, the leads 7 from which extend to oppositely disposed contacts 8 mounted on an insulation disc 9 fixed on the shaft 3. Spring contact strips 10, insulated from each other and mounted in connection with the bracket structure 1, are adapted to engage the contacts 8 simultaneously only when the disc 9 is in certain positions. A lead 11 from one strip 10 is connected with the lead to the tail lamp 12 of the vehicle, while the lead 13 from the other strip 10 is grounded at a suitable point.

By means of this construction, the lights will never be lit unless the tail light 12 is on, which of course is only at night. Further, the contacts 8 are so located on the discs 9 with respect to the axial lines of the signal arrows that the strips 10 will only engage therewith, so as to close the circuit to the lamps, when said arrows are pointing in a horizontal direction either to the right or left.

Movement is imparted to both signal members simultaneously, and so that they rotate in the same direction, by means of racks 14, mounted in spaced and opposed relation to each other in a casing 15 fixed to the vehicle and preferably positioned under the front or driver's seat thereof. A pinion 16 is mounted in said casing between the racks and engages them both, an operating handle 17 connected to the pinion projecting forwardly of the casing to within convenient reach of the driver's hand.

Flexible wires 18 extend from the rear ends of the racks to the lower ends of bell cranks 19 pivoted on the brackets 1 below the shafts 3, said wires being enclosed and guided in tubes 20.

On the upper ends of the bell cranks are segmental gears curved concentric with the axes of said bell cranks, which mesh with pinions 22 fixed on the shafts 3.

The toothed members are so proportioned with relation to each other that with a pre-

determined arc of throw of the handle 17, the signals 4 will be moved through a complete half-turn, or from a horizontal position pointing to the left, to a similar position pointing to the right, or vice-versa.

The members 20 are arranged in opposite relation to each other, so that both signals will turn in the same direction when one rack 14 moves back and the other forward, 10 which will of course be the relative movement imparted thereto with the rotation of the pinion 16.

These racks are set at an angle to each other so that the wires 18 may run in a substantially straight line from the racks to the lower ends of the members 20.

The pinions 22, discs 9, and co-operating parts adjacent thereto are enclosed in housings 23 of suitable design.

20 From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended 30 claims.

Having thus described my invention, what I claim as new and useful and desire to secure by Letters Patent is:

1. A direction signal structure for vehicles 35 comprising a pair of turnable shafts extending longitudinally of the vehicle on opposite sides thereof, signal members mounted on the shafts at right angles thereto, pinions on the shafts, bell cranks arranged in opposed relation to each other mounted in fixed relation with the shafts, segmental gears on one end of the bell cranks, and means applied to the free ends of the latter 40 for moving the same simultaneously and in opposite directions.

2. A direction signal structure for vehicles comprising pivoted signal members mount-

ed on both sides of the vehicle and arranged for transverse swinging movement, both signals pointing in the same direction laterally of the vehicle, a turnable handle, and means whereby with the turning of said handle both signals will be swung simultaneously and in the same direction.

3. A direction signal structure for vehicles comprising a pair of turnable shafts extending longitudinally of the vehicle on opposite sides thereof, signal members mounted on the shafts at right angles thereto, pinions on the shafts, lever members pivoted in fixed relation with the shafts, segmental gears on the outer ends of said members meshing with the pinions, and flexible members by means of which said levers may be moved from a distance simultaneously and in opposite directions connected thereto.

4. A direction signal structure for vehicles comprising a pair of shafts extending longitudinally of the vehicle and mounted on opposite sides thereof, signal members mounted on the shafts at right angles thereto, pinions on the shafts, bell cranks arranged in opposed relation to each other mounted in fixed relation with the shafts, segmental gears on one end of the bell cranks meshing with the pinions, flexible members from the opposite ends of the cranks, and means for moving said members in opposite directions simultaneously.

5. A direction signal for vehicles comprising a support adapted to be mounted on a fender of the vehicle, a shaft turnably mounted in the support in a plane longitudinally of the vehicle, a signal member mounted on the shaft at right angles thereto, a pinion on the shaft, a bell crank pivoted on the support, a segmental gear on one end of the bell crank and meshing with the pinion, and means connected to the other end of the bell crank for moving the same.

In testimony whereof I affix my signature:

JOSEPH F. LYNCH.
